UNITED STATES PATENT OFFICE.

CHARLES H. NOTTER, OF CHICAGO, ILLINOIS, ASSIGNOR TO THE W. S. BOGLE COMPANY, OF SAME PLACE.

RELEASING DEVICE FOR TRAM-CAR DOORS.

SPECIFICATION forming part of Letters Patent No. 540,682, dated June 11, 1895.

Application filed August 24, 1894. Serial No. 521,197. (No model.)

To all whom it may concern:

Be it known that I, CHARLES H. NOTTER, of Chicago, Illinois, have invented certain new and useful Improvements in Releasing Devices for Tram-Car Doors, of which the following is a specification.

This invention relates to an automatic releasing device for the bolts or fastenings of tram-car doors.

10 In the operation of tram-cars, they are dispatched in a loaded condition over a track or tram-way and at certain points on the line it is desired to discharge the contents of the cars automatically, thus dispensing with 15 manual attendance and operation; and my invention is designed to furnish a simple and efficient means for releasing the bolts which confine the pivoted or swinging doors, forming the sides of the tram-car, automatically, 20 by contact with a stationary block or tripping device located along the line of track.

In the accompanying drawings, Figure 1 is a broken side elevation, and Fig. 2 a transverse sectional view, of a tram-car having applied thereto my improvements.

The car is usually mounted upon a four wheel truck, and its side walls A A are hinged at their upper edges—as, for example, on the rods B. The car C has a keeper D secured thereto, and a vertically moving locking bolt E, which is confined to move through the keepers F, its lower end dropping into keeper D to lock the door. The sides of the car are flared outwardly, and, therefore, when the 35 bolt is released the door will swing open by gravity to the position shown by the dotted lines in Fig. 2. Now, in order to release the locking bolt, I pivot a lever G thereto, said lever being pivoted as at g to the sides of 40 the car and between its ends to the upright or vertical bar H. Said bar projects below the bottom of the car, and preferably carries upon its end a roller h, which is adapted to strike a stop wedge or block I, fixed in proper 45 position along the line of track. The bar H may be confined in position by the keepers which confine the locking bolt, and it preferably has pivotally connected thereto at its upper end a hand lever J, pivoted on the side 50 of the car and by which the locking bolt may be raised in position to enter its keeper in

fastening the door in the closed position. In operation, however, the device is rendered automatic by the engagement of the anti-friction roller on the end of the vertical slideable bar with the stop wedge fixed along the line of track at the position where it is desired to dump the load. The car may, therefore, be sent on its circuit loaded, and when it passes over the stop wedge the fastening bolt will be released from its keeper and the door will swing out or be forced out by the load, and the latter will be discharged without interrupting the progress of the car or manual attendance. The door remains open 65 until the car approaches the loading station when it will be closed by an attendant.

While the construction of the several parts may be varied, and while the invention may be applied to many forms of tram cars, I consider the means herein shown as the best known to me.

I claim—

1. A releasing device for the fastenings of tram-car doors, comprising in combination with a swinging door, a slideable bolt mounted thereon, a keeper for said bolt arranged adjacent to the free edge of the door, a lever pivotally connected to the bolt and to the body of the car, a slideable bar pivotally connected to said lever and projected below the car and a fixed obstruction or tripping block arranged along the way and with which the sliding bar is adapted to engage, substantially as described.

2. In means for releasing the fastenings of tram-car doors, the combination with a slideable bolt mounted on the door, a keeper secured to the frame of the car adjacent thereto, a lever pivoted to the bolt and to the side of the car, a vertically slideable bar pivotally connected to said lever and having its end projected below the car and provided with a roller, a hand lever pivoted to the car and to said bar, and a tripping block fixed along the line of way and adapted to engage the roller, substantially as described.

CHARLES H. NOTTER.
